ABSTRACT: This invention relates to card retrieval systems of the type in which card selection from a deck of similar cards which are magnetically responsive and randomly stored in vertical face-to-face relation is effected by laterally shifting, under the force of a movable magnet, one or more of the stored cards while restraining against movement the undesired cards, thereby physically separating the desired cards from those not desired. More particularly, this invention relates to a magnet-shifting method and apparatus useful in systems of the type described which reduces the breakaway, or maximum, force which must be applied to the magnet before it can become disengaged from the undesired cards and, by further movement, increase the separation between the desired and undesired cards.

**MAGNET SHIFTING MECHANISM FOR RETRIEVAL
SYSTEM UTILIZING MAGNETICALLY RESPONSIVE
CARDS**

A card retrieval system of the type with which the magnet-shifting method and apparatus of this invention finds an extraordinarily high degree of utility is disclosed and claimed in the copending application of Robert D. Parry, for **ARTICLE SELECTION SYSTEM**, Ser. No. 661,758, filed Aug. 4, 1967, now U.S. Pat. No. 3,478,877. In accordance with the Parry system, a plurality of rectangular cards are provided, each having teeth formed along a sorting edge, preferably the bottom edge, which are selectively removable for coding purposes and which are spaced from each other by intermediate registration notches. The cards are also provided with a lock notch and removed corner section. The lock notch and removed corner section are positioned along the sorting edge between the group of removable teeth and their associated registration notches, and an adjacent card side edge herein termed the "trailing edge." The card further includes a ferromagnetic implant or chip mounted in the vertical edge of the card opposite the trailing edge, herein termed the "leading edge."

A plurality or deck of cards, numbering up to approximately 2,000 cards, are randomly stored in face-to-face vertical relation in a card selector apparatus. The card selector apparatus is provided with a horizontally disposed planar slotted platen which supports the upstanding cards. The orientation of the platen and cards relative to each other is such that the code-notched sorting edges of the randomly stored cards rest on the platen with their sorting edges transverse to the platen slots. Disposed in the platen slots are a plurality of code, or sort, bars corresponding in number to, and aligned with, the registration notches formed by the spaces between the code-notchable teeth. The sort bars, which normally are positioned with their upper edges flush with the top surface of the platen, are selectively elevatable to an upper, or set, position wherein their upper edges protrude above the platen into the associated card registration notches of the stored cards. Located parallel to the sort bars and opposite the lock notches of the stored cards is a transversely disposed lock bar which is selectively elevatable to a card lock position. In the card lock position the lock bar is susceptive of being positioned in the lock notches of those cards whose lock notches are aligned with the lock bars. An elongated magnet is transversely disposed relative to the stored cards opposite and in alignment with the ferromagnetic chips implanted in the leading edges of the cards. The elongated magnet is mounted on a drawerlike structure for movement toward and away from the implanted ferromagnetic chips of cards positioned in their normal stored position on the platen, that is, the magnet is mounted for movement in a direction parallel to the sorting edges of the stored cards.

Card selection in the Parry retrieval system is effected in two sequential phases, namely, an initial separation phase and a final separation phase. The initial separation phase is accomplished by elevating or setting the sort bars in a pattern conforming to the removed tooth pattern of the desired card or cards, and thereafter moving the magnet a distance equal to one tooth in a direction parallel to the sorting edge. Ideally the desired cards, that is, the cards having a removed tooth pattern conforming to that of the set sort bars, shift laterally in the direction of their sorting edges a distance equal to the width of one tooth, and in so doing align their removed corner sections in the trailing edge with the lock bar. This movement is possible because the teeth of the desired cards located adjacent to the set sort bars are removed by virtue of the code-notching process. The undesired cards, that is, those cards with a nonconforming removed tooth pattern, are not free to move in a direction parallel to their sorting edge, and consequently remain stationary, leaving their trailing edge lock notches aligned with the lock bar. Once initially separated, the desired cards are further separated from the undesired cards to effect the final separation phase by moving the magnet

further in a direction parallel to the card-sorting edges an additional distance, the magnitude of which depends on the amount of separation between the selected and unselected cards which is ultimately desired.

5 However, prior to moving the magnet the additional distance necessary to effect further separation of the desired and undesired cards, the lock bar is elevated to engage the lock notches of the unselected cards which have remained stationary and aligned with the lock bar during the initial phase of magnet movement. The elevated lock bar does not engage the lock notches of the desired cards because these cards, in the course of the initial separation phase of the retrieval process, shifted relative to the undesired cards in a direction parallel to their sorting edges a distance sufficient to locate the lock bar in transverse registry with the removed corner sections of the desired cards. With the lock notches of only the undesired cards engaged by the set lock bar, the sort bars are reset and the magnet moved further in a direction parallel to the sorting edge. This further separates the desired cards from the undesired cards which are positively restrained from movement by the lock bar which engages their lock notches. Thus, the lock bar positively prevents, during the final separation phase, selection of undesired cards.

20 In the preferred card selector embodiment disclosed in the previously referenced Parry patent application, the initial phase of the card retrieval cycle is accomplished by moving the elongated magnet in a direction parallel to the card-sorting edges for a distance equal to the width of one tooth while at all 25 times maintaining the magnet parallel to its position at the start of the sorting cycle, namely, parallel to the sorting bars. When the initial card separation phase of the retrieval cycle is effected in the manner indicated, wherein the magnet at all 30 times remains parallel to its starting position, the individual attractive forces between the magnet and each unselected card chip diminish to zero at approximately the same instant of time in the course of magnet travel. Stated differently, when the magnet moves in parallelism in the manner indicated in connection with the Parry selector, the magnet "breaks away" 35 from each individual unselected card chip at substantially the same instant.

40 In a card selector of the Parry type, where breakaway occurs simultaneously for all unselected cards, the force which must be applied to the magnet to enable such breakaway is relatively large. The reason for this is that until the magnet actually breaks away, forces of attraction continue to exist between the chip of every undesired card and the magnet. In a typical 2,000 card capacity selector, wherein in any given card retrieval cycle only a few cards are likely to be selected, the breakaway force which must be overcome between the magnet and the bulk of the cards is on the order of 200 lbs. With forces of such magnitude, the cost of the magnet drive motor means is undesirably large, and hence objectionable.

45 It has been an objective of this invention to provide a card selection method and apparatus which significantly reduces the forces which must be applied to the magnet of a Parry type selector during the initial phase of the card-sorting cycle to enable the magnet to overcome its attraction to the chips of the unselected cards, and thereby break away and move freely 50 to further separate the desired cards from those not desired. This objective has been accomplished in accordance with certain of the principles of this invention by utilizing an entirely different approach to the manner into which the magnet is moved during the initial phase of the card retrieval cycle. Specifically, this objective has been accomplished by, during 55 the initial stage of the card retrieval cycle, first initiating advancement of one end of the magnet, thereby skewing or canting the magnet relative to its position at the start of the cycle, and thereafter initiating advancement of the other end of the magnet ultimately restoring the magnet to its condition of parallelism. By virtue of such noncoincidental magnet end region movement, the magnet end regions break away from their associated groups of undesired cards at different times in 60 the course of the initial phase of the card retrieval cycle,

thereby reducing the maximum force which must be applied to the magnet to permit it to break away from the unselected cards. With the breakaway force reduced, the drive assembly which shifts the magnet is simplified, and the required starting torque for the motive means which operates the drive assembly is substantially reduced, decreasing the power requirements of the magnet motor means.

It has been a further objective of this invention to provide simple and inexpensive means for maintaining magnet parallelism throughout the subsequent or final separation phase of the retrieval operation once such parallelism has been restored at the end of the initial phase of the card retrieval cycle. This objective has been accomplished in accordance with certain additional principles of this invention by the extraordinarily simple expedient of providing a rack mounted for movement with the magnet in a direction parallel its longitudinal axis, and a pinion rotatably mounted about a stationary axis which initiates meshing engagement with the rack once the magnet has been restored to its position of parallelism upon completion of the initial phase of the card retrieval cycle. An advantage of such a rack and pinion arrangement is that in the event an offcenter force is applied to the magnet during the final phase of the retrieval cycle in an effort to further separate the desired and undesired cards, the magnet will not skew or cant. By eliminating the possibility of skewing or canting, the magnet mounting structure can be simplified, at least to the extent that it need not be designed to avoid binding between the moveable magnet and the stationary magnet supporting structure should offcenter forces be applied to the magnet during the final phase of the card retrieval cycle.

This and other objectives and advantages of the invention will become more readily apparent from a detailed description of a preferred embodiment thereof taken in conjunction with the drawings in which

FIG. 1 is a perspective view of the front of the preferred embodiment of this invention.

FIG. 2 is a perspective view, partially broken away, of the rear of the preferred embodiment.

FIGS. 3A-3E are schematic side elevational views of a card selector showing the relationship, during different phases of a card retrieval cycle, of the drawer, magnet, platen, sorting and lock bars, and desired and undesired cards.

FIG. 4 is a top elevational view, partially broken away, of the preferred embodiment showing the relationship of the cam, bellcranks, drawer-mounted magnet, and the racks and pinions at the beginning of the card retrieval cycle when the cam is in its home position.

FIG. 5 is a longitudinal cross sectional view of a portion of the preferred embodiment.

FIG. 6 is a plot of the drawer and magnet displacement versus the angular rotation of the cam.

FIGS. 7, 8, 9, and 10 are top elevational views similar to FIG. 4 of the preferred embodiment showing the relation of the cam, bellcranks, drawer-mounted magnet, and the racks and pinions during different phases of the card retrieval cycle.

FIG. 11 is a cross-sectional view showing a single rack and pinion combination which cooperate to maintain the drawer and magnet in a condition of parallelism during the final phase of the card retrieval cycle.

For the purpose of more easily understanding the magnet drive mechanism of this invention, the invention is described in connection with a card retrieval system of the general type disclosed in the previously referenced Parry application, the entire disclosure of which is specifically incorporated herein by reference. The Parry retrieval system, as best seen in FIGS. 1 and 2, includes a keyboard control console 10 and a card selector 12. The keyboard console 10 preferably is of the type disclosed and claimed in the copending application of Robert J. Kalthoff et al. for "Console and Control Circuit," Ser. No. 539,792, filed Apr. 4, 1966 now U.S. Pat. No. 3,450,261, the entire disclosure of which is expressly incorporated herein by reference. The card selector 12 includes, enclosed within a

housing 13, a stationary horizontally disposed planar platen 20 which supports a deck of randomly stored vertically disposed cards 22. A transversely disposed elongated magnet 24 common to all the cards 22 and in alignment with ferromagnetic chips 23 implanted in the leading edges of the cards is secured to a drawerlike structure 26 for sliding movement between an outer position (FIGS. 1 and 3E) to which desired cards are advanced in a manner to be described and an inner position (FIGS. 3A and 3B) in which the magnet 24 is in contact with the ferromagnetic implants 23 when the cards are stored in their normal position.

As best seen in FIGS. 3A-3E, the cards 22 each have a toothed sorting edge 32, preferably the lower edge thereof, provided with alternate teeth 34-1 to 34-6 and registration notches 35-1 to 35-6. Each of the teeth 34-1 to 34-6 is susceptible of being encoded in binary by selective as by notching, of the respective tooth. The sorting edge 32 further includes a lock notch 36 located between a group of encodeable teeth 34 and registration notches 35, and the transverse card edge 38 herein termed the "trailing edge." Adjacent to the lock notch 36 is a removed portion 40 of the card located intermediate the lock notch 36 and the trailing edge 38. The card 22 further includes the ferromagnetic chip 23 implanted in the card at the corner of the sorting edge 32 and a transverse edge 44 herein termed the "leading edge."

When the cards 22 are in their normal unselected position on the platen 20 of the selector 12, the registration notches 35-1 to 35-6 and the lock notch 36 are aligned with a plurality 30 of transversely disposed sort bars 48-1 to 48-6 and a lock bar 50 which are disposed transverse to, and in common with, all the cards. Both the sorting bars 48-1 to 48-6 and the lock bar 50 are appropriately positioned in slots formed in the upper surface of the platen 20. The bars 48-1 to 48-6 and 50 are elevatable from a reset position wherein their upper edges are flush with the upper surface of the platen to a set position wherein they enter their associated notches 35-1 to 35-6, and 36, respectively, of cards located in the storage position. Elevation of the bars 48-1 to 48-6 and 50 is effected by solenoids (not shown) controlled by the keyboard console 10.

To select a card or cards 22 having a particular code, for example, a card 22a having teeth 34-2 and 34-6 removed, from among a group of cards 22b not having teeth 34-2 and 34-6 removed, the appropriate sort bars 48 are elevated to the set position. Specifically, sort bars 48-2 and 48-6 corresponding to the removed tooth pattern of the desired card 22a are elevated to the position shown in FIG. 2B. With the sort bars 48-2 and 48-6 in a set position, the desired cards 22a having teeth 34-2 and 34-6 removed can be laterally shifted in the direction 46a of arrow 46 a distance equal to the width of one tooth, to produce an initial separation of the desired cards from the undesired cards. However, the undesired cards 22b not having tooth 34-2 and/or tooth 34-6 removed are restrained from lateral movement in the direction 46a of arrow 46 by one or both of the set or elevated sort bars 48-2 and 48-6, which, in the set position, mechanically interfere with the unremoved teeth 34-2 and 34-6 of the undesired cards 22b.

With the sort bars 48-2 and 48-6 conforming to the removed tooth pattern of the desired card 22a in the set position, the magnet 24 is shifted in the direction 46a of arrow 46 a distance equal to the width of one tooth to the position shown in FIG. 2C. Those cards free to shift, namely, the desired cards 22a move with the magnet 24 a distance of one tooth width, effecting an initial separation of the desired and undesired cards. Movement of the desired cards 22a in this fashion aligns the removed portion 40 of the desired cards opposite the lock bar 50. The undesired cards 22b do not move in the direction 46a of arrow 46 by reason of the engagement of one or more of their unremoved teeth 34-2 and 34-6 with the set sort bars 48-2 and 48-6, respectively. Consequently, the lock notches 36 of the undesired cards 22b remain aligned with the lock bar 50. At this point the initial phase of the card selection operation is complete.

Further separation of the desired cards 22a from the undesired cards 22b to effect the final card selection phase of the retrieval operation is accomplished by elevating to a set position the lock bar 50, and to an unset position the sort bars 48-2 and 48-6, as shown in FIG. 3D. Setting lock bar 50 positively prevents the undesired cards 22b from moving in response to the continued movement of the magnet 24 in the direction 46a of arrow 46. Resetting or lowering the set sort bars 48-2 and 48-6 after the initial card separation phase enables the selected cards 22a to continue movement in the direction 46a of arrow 46 in response to movement of the magnet 24 in this direction, the desired cards 22a being free to move in this direction by reason of the removed portion 40 thereof being aligned with the elevated or set lock bar 50. With the lock bar 50 set and the sort bars 48 all in their lower, reset position, the magnet 24 is advanced further in the direction 46a of arrow 46 to the position shown in FIG. 3E, further separating the desired cards 22a from the undesired cards 22b. At this point, the final card selection phase of the retrieval cycle is complete, marking the completion of the entire card retrieval operation.

The card selector 12, considered in more detail in conjunction with FIGS. 1, 2, 4 and 5, includes the housing 13 having a bottom surface 13A, a rear surface 13B, opposite side surfaces 13C and 13D, a front surface 13E provided with a suitably configured removed portion for accommodating the drawer 26, and an upper surface 13F. The housing 13 may be fabricated of any suitable material, such as sheet metal. Located within the housing 13 is the horizontal planar platen 20 provided with suitable transverse slots for receiving the vertically shiftable code bars 48 and lock bar 50. The platen 20 is secured by means (not shown) to the top surfaces 55 and 56 of stationary guide blocks 57 and 58 which in turn are secured to the upper surface of a stationary frame plate 54. Also enclosed within the housing 13 and positioned beneath the platen 20 is a sliding plate 53 to which is secured the drawer 26 which mounts the magnet 24. The opposite side edges 59 and 60 of the sliding plate 53 are slidably positioned in guide slots 61 and 62 formed in the guide locks 57 and 58. The guide slots 61 and 62 cooperate with the plate edges 59 and 60 to mount the plate 53, and hence the drawer 26 and magnet 24, for reciprocal movement in the direction of arrows 46a and 46b. The depth of the slots 61 and 62 measured in the direction of the longitudinal axis of the magnet 24 is greater than the mating portions of edges 59 and 60 of the plate 25 measured in the same direction to permit the plate 53 to skew in the slots, for reasons to become evident hereafter.

To effect movement of the sliding plate 53 in the direction of arrow 46a, and hence movement of the drawer 26 and 24, as is necessary to complete the initial and final card selection phases of the card retrieval cycle, a magnet shifting mechanism generally indicated by the reference numeral 64 is provided. The magnet shifting mechanism 64 includes a cam 63 which is mounted for rotation with a vertical shaft 65 fixed at its upper end to the cam center. The shaft 65 is rotatably mounted by a suitable stationary bushing 66 fixed in the bore 67 of a boss 68 formed integral with the upper surface of the frame support plate 54. The lower end of the shaft 65 is secured to a sprocket 70 which is driven by drive sprocket 72 via a chain 71. Drive sprocket 72 is powered by a motor 73 mounted to the upper surface of the frame support plate 54. Motor 73 has a shaft 74 extending downwardly through a suitable aperture in the frame support plate. Shaft 74 is connected to the sprocket 72.

Cooperating with the cam 63 are identically constructed bellcranks 28 and 29. The bellcranks 28 and 29 are mounted for rotation about vertical axes by stationary shafts 76 and 77 which are anchored in the upper surface of the frame support plate 54. Shafts 76 and 77 pass through suitable bushings 78 and 79 formed integral with the intermediate portions of the bellcranks 28 and 29. Each of the bellcranks 28 and 29 has a pair of legs 28A, 28B and 29A, 29B, respectively. Mounted at the ends of the legs 28A and 29A of bellcranks 28 and 29 are

rotatable cam follower wheels 80 and 81 which cooperate with a peripheral cam surface 69 formed on the cam 63 to be described in detail hereafter. Mounted at the ends of the legs 28B and 29B of bellcranks 28 and 29 are drive blocks 82 and 83 which are adapted to engage suitably positioned stops 84 and 85 fixed to the inner surface of the drawer 26 for transmitting to the drawer, and hence to the magnet 24 supported thereby, force applied by the cam surface 69 to the followers 80 and 81 during the initial phase of the card retrieval operation. The cam 63, in addition to the peripheral cam surface 69 which cooperates with the bellcrank mounted cam followers 80 and 81 for imparting motion to the magnet 24 during the initial phase of the card retrieval cycle, also includes a cam drive wheel 87 mounted for rotation about a vertical axis via a pin 88 anchored at its lower end in the upper surface of the cam 63. The cam drive wheel 87 is adapted to engage a cam follower edge 89 formed in the rear of the sliding plate 53 for imparting positioning motion to the drawer 26, and hence to the magnet 24, during the final phase of the card retrieval cycle.

Referring to FIG. 6, the cam 63 which is shown in its home or 0° position, is seen to include four lobes A, B, D and D' formed on the peripheral cam edge 69. Cam lobe A, when the cam 63 rotates through an angle of 15° in the counterclockwise direction from the 65° point to the 80° point is adapted to impart 0.125 inches of movement to the stop member 84, and hence to the right hand side of the magnet 24, as viewed in FIG. 7. Cam lobe B, when the cam wheel 27 rotates from the 80° point to the 97° point, is adapted to impart 0.125 inches of displacement to the cam follower wheel 81, and hence to the stop 85 and the left-hand portion of the magnet 24, as viewed in FIG. 8. The combination of cam lobes A and B functions to advance the drawer 26, and hence the magnet 24, during the initial phase of the card retrieval operation in a skewed manner. Specifically, in the initial phase of the card retrievable cycle cam lobe A advances the right hand side of the magnet 24 a distance equal to 0.125 inches, whereafter cam lobe B advances the left hand side of the magnet the same distance. Upon completion of engagement of cam lobe B at the 97° point with its associated cam follower wheel 81, the magnet 24 is parallel to the chips 23 of the stored cards, and the initial phase of the card retrieval cycle which began at the 65° point is completed.

Cam lobes D and D' are located on diametrically opposite edges of the cam disc periphery 69, and as a consequence thereof simultaneously engage their respective cam follower wheels 81 and 80. The cam lobes D and D', when the cam 27 rotates counterclockwise from the 165° point to the 170° point in the cam cycle are adapted to impart equal and simultaneous displacements of 0.125 inches to their associated cam followers 81 and 80 for imparting, in turn, equal and simultaneous displacements of 0.125 inches to the drawer 26, which is now parallel to the chips of the stored cards, for reasons to be described.

The cam drive wheel 87, when the cam 63 rotates from the 200° point in the cycle to the 330° point, engages the cam follower edge 89 of plate 53, driving the plate 53 and, hence the drawer 26 and magnet 24, from its position displaced 0.25 inches from the home position through an additional displacement of 1.75 inches. At the 330° point the magnet 24 has been displaced a total distance of 2 inches, and the final phase of the card separation cycle, which began at the 165° point, is now complete.

To insure maintenance of proper realignment of the magnet 24, which during the initial phase of the card retrieval cycle is advanced in a skewed fashion by the time displaced engagement of cam lobes A and B with their respective cam follower wheels 80 and 81, a pair of racks 95 and 96 which cooperate with a pair of pinions 97 and 98 are provided. The racks 95 and 96 are secured to the lower surface of the guide edges 59 and 60 of the sliding plate 53, and have teeth on their lower surfaces which mesh with the peripheral teeth of the pinions 97 and 98. The pinions 97 and 98 are fixed to the ends of a

shaft 99 which is rotatably mounted for rotation about its axis by a pair spaced journal blocks 92 and 93 secured to the upper surface of the frame support plate 54. The length and position of the racks 95 and 96 relative to the pinions 97 and 98 are such that meshing engagement of the racks and pinions begins at the 165° point of cam rotation when the cam lobes D and D' advance the opposite ends of the magnet 24 which are rendered parallel to the chips 23 of the stored cards at the 97° point when cam B completes engagement with its associated follower 81. The racks 95 and 96 and cooperating pinions 97 and 98 insure that the magnet 24 remains parallel to the chips 23 of the stored cards during the final phase of the card retrieval cycle. By maintaining this parallelism during the final stage of the card retrieval cycle the sliding plate 25 does not become skewed or canted relative to the guide slots 61 and 62 of guide blocks 57 and 58 as the cam drive wheel 87 engages the cam follower 89 of the plate, driving the magnet 24 outwardly to effect the final card separation phase of the retrieval cycle.

Prior to the start of a card retrieval cycle, the drawer 26 is in its innermost position as shown in FIG. 4, bringing the magnet 24 in contact with the chips 23 of the stored cards as best shown in FIG. 3A. Additionally, the cam 63 is in the home position shown in FIG. 4. To initiate a card retrieval cycle, the sort bars 48 corresponding to the removed notch pattern of the desired cards 22a are elevated from the reset position shown in FIG. 3A to the set position shown in FIG. 3B by activating the appropriate keys of the console 10. Thereafter the motor 73 is energized, by activation of a suitably provided start key on the console 10 which initiates rotation of the cam 63 through a cycle of 360°. For the first 65° of rotation of cam 63 from the 0° point to the 65° point (designated region K in the plot of magnet displacement versus cam rotation of FIG. 6), the cam follower wheels 80 and 81 are not displaced and hence the drawer 26 and magnet 24 remain stationary. Starting at the 65° point in the cam rotation cycle and continuing through the 80° point, cam follower wheel 80 engages cam lobe A, moving the right hand side (as viewed in FIG. 4) of the drawer 26, and hence of the magnet 24, through a displacement of 0.125 inches, from the position shown in FIG. 4 to the position shown in FIG. 7. During this movement of the right-hand side of the drawer 26, which is designated region A in the plot of FIG. 6, the desired cards 22a in the right hand section of the selector having a notch pattern conforming to that of the set bars 48 are advanced to effect a partial separation from the remaining undesired cards 22b. The undesired cards 22b in the right-hand section of the selector, which do not have a notch pattern conforming to that of the set bars, are restrained from movement by the set bars and accordingly their chips 23 disengage the magnet 24.

As the cam 27 rotates from the 80° point of the cycle to the 97° point, designated region B in the plot of FIG. 6, the left hand side of the drawer 26, and hence of the magnet 24, advances 0.125 inches from the position shown in FIG. 7 to the position shown in FIG. 8. During this portion of the cycle the desired cards 22a in the left-hand section of the selector 12 having a pattern of notches conforming to that of the set bars are partially selected from the remaining undesired cards 22b not having such a conforming notch pattern. At this point the magnet 24 along its entire length has been advanced 0.125 inches from its initial or home position depicted in FIG. 4, separating all desired cards 22a a distance of 0.125 inches from the remaining undesired cards 22b as shown best in FIG. 3C. At this point in the cam cycle, which is the 97° point in the plot of FIG. 6, the initial separation phase of the card retrieval cycle which began at the 65° point is complete, and the drawer 26 is in the position shown in FIGS. 3C and 8.

Further rotation of the cam 63 from the 97° point to the 165° point, which is designated region C in the plot of FIG. 6, does not produce movement of the magnet 24. However, during this portion of the cam cycle the previously set sort bars 48 are reset and the lock bar 50 elevated to a set position to restrain movement of the undesired cards 22b. The magnet

24, cards 22, sort bars 48 and lock bar 50 now occupy the positions shown in FIG. 3D.

As the cam 63 rotates from the 165° point to the 170° point designated region D, D' in the plot of FIG. 6, the cam lobes D and D' engage their respective cam follower wheels 81 and 80, moving the magnet 24 a distance of 0.125 inches in the direction of arrow 46a, from the position shown in FIG. 8 to the position shown in FIG. 9. During rotation of the cam 27 from the 165° point to the 170° point, the racks 95 and 96 secured to the bottom of the sliding plate 53 which moves with the magnet 24 engage the stationary rotatable pinions 97 and 98, insuring that the drawer 26, during the final separation phase of the retrieval cycle, remains parallel to chips 23 of the stored cards.

Continued rotation of the cam 63 from the 170° point to the 200° point, designated region F in the plot of FIG. 6, is ineffective to further advance the drawer 26. However, at the 200° point the cam drive wheel 87 engages the cam follower edge 89 of the sliding plate 53. As the cam plate rotates from the 200° point to the 330° point, designated region G in the plot of FIG. 6, the cam drive wheel 87 advances the plate 53, and hence the drawer 26 and magnet 24, a distance of 1.75 inches from the position shown in FIG. 9 to the position shown in FIG. 10. This movement of magnet 24 further separates the desired cards 22a from the undesired cards 22b, advancing the desired cards to the position shown in FIG. 3E. When the cam 63 has rotated to the 330° point (FIG. 10) the final separation phase of the card retrieval cycle, which began at the 165° point (FIG. 3D and 8), is completed, and further rotation of the cam 63 from the 330° point to the home, 360° or 0° point (designated region J in the plot of FIG. 6) is ineffective to advance the selected cards 22a beyond the point shown in FIG. 3E. When the cam 63 has rotated to the home, 360° or 0°, position, the motor 73 is deenergized by suitable means (not shown) and the cam stops.

From the foregoing description of the operation of the preferred embodiment, it is apparent that the manner in which the cam lobes D and D' cooperate with the bellcrank mechanisms 28 and 29 to initially shift the magnet 24 in a skewed or canted fashion is effective to produce breakaway between the magnet and the chips 23 of the unselected cards in a time-staggered fashion. With breakaway between the magnet 24 and undesired card chips 23 time-staggered, the maximum force which must be applied to the magnet to effect breakaway is substantially reduced, permitting smaller and less powerful magnet shifting mechanisms to be utilized.

I claim:

1. Apparatus for relatively moving a support having a plurality of aligned cards positioned thereon and a magnet disposed transversely of said cards in magnetically attractive relationship to ferromagnetic chips secured thereto, said apparatus comprising:

a cam rotatably mounted on one of said support and magnet, said cam having an edge with first and second lobes; and

a pair of bellcranks each pivotally mounted on said one of said support and magnet adjacent opposite sides of said cam edge, said bellcranks each having

a. a cam follower arm engageable with a different one of said cam lobes for pivoting its respective bellcrank when its associated lobe contacts said cam follower arm, and

b. a pushing arm engageable with the other of said support and magnet at a different region for relatively moving said region and said one of said support and magnet when its respective bellcrank pivots, said lobes and said bellcranks being dimensioned and configured relative to each other such that said different regions move relative to said one of said support and magnet in skewed relationship, thereby enabling said magnet to break away from said chips in a time-staggered manner.

2. The apparatus of claim 2 wherein said cam lobes are non-diametral, wherein said cam and bellcranks are rotatably and

pivotedly mounted, respectively, on said card support, and wherein said bellcranks are identically configured and their respective cam follower arms located at diametrically opposite positions relative to said cam, whereby said cam lobes pivot their respective bellcranks, imparting motion to said magnet regions, in a time-staggered manner as said cam rotates.

3. In apparatus for selecting cards having a sorting edge with alternate registration notches and code notched teeth from a plurality of different cards supported with their respective sorting edge aligned, each of said cards having a magnetically responsive portion thereon, wherein the apparatus includes a plurality of sorting bars disposed transversely of said sorting edges adjacent said registration notches, a sorting bar actuator for selectively moving said sorting bars into different ones of 15 said registration notches of said cards, an elongated magnet having opposite end regions and disposed adjacent said magnetically responsive portions of said cards for attracting said cards and being shiftable in a direction parallel to said sorting edges for partially separating cards having their respective 20 teeth notched in conformity with the pattern of actuated sorting bars from cards not conformingly notched, the improvement which comprises:

a magnet-shifting mechanism including

- a. a first drive member operatively associated with one of 25 said magnet end regions for shifting said one end region to thereby partially separate conformingly and nonconformingly notched cards associated with said one magnet end region,
- b. a second drive member operatively associated with the other of said magnet end regions for shifting said other end region to thereby partially separate conformingly and nonconformingly notched cards associated with said other magnet end region, and
- c. operating means for said drive members for operating said first and second drive members to noncoincidentally shift said one and other magnet end regions, thereby partially separating said cards in a time-staggered manner.

4. The improvement of claim 3 wherein said first and second drive members include first and second pivotedly mounted bellcranks, said bellcranks each having a cam follower arm and a magnet pushing arm, the pushing arms of said bellcranks being engageable with different ones of said magnet end regions, and wherein said operating means includes a rotatably mounted cam having first and second lobes adapted to engage different ones of said cam followers, said lobes and bellcranks being dimensioned and configured relative to each other such that said pushing arms noncoincidentally impart motion to said magnet end regions thereby partially separating said desired and undesired cards in said time-staggered manner.

5. In apparatus for selecting desired cards each having a predetermined notch pattern along a sorting edge and a ferromagnetic member in a transverse edge from undesired cards each having a different notch pattern and a ferromagnetic member, wherein the apparatus includes support for supporting the cards with their respecting sorting and transverse edges and ferromagnetic members aligned, a plurality of sorting bars disposed transversely of said sorting edges adjacent said notches, a sorting bar actuator for selectively moving said sorting bars into different ones of said registration notches, and an elongated magnet having opposite end regions

disposed adjacent the ferromagnetic members of first and second groups of associated cards for attracting said different groups of cards and being shiftable in a direction parallel to said sorting edges for partially separating said desired and undesired cards, the improvement comprising:

a magnet-shifting mechanism including

- a. a first drive member operatively associated with one of said magnet end regions for shifting said one end region to thereby partially separate desired and undesired cards associated with said one magnet end region,
  - b. a second drive member operatively associated with the other of said magnet end regions for shifting said other end region to thereby partially separate desired and undesired cards associated with said other magnet end region, and
  - c. operating means for said drive members for operating said first and second drive members to noncoincidentally move said one and other magnet end regions, thereby partially separating said desired and undesired cards in a time-staggered manner,
- at least one rack mounted for movement with said magnet in a direction substantially parallel to its longitudinal axis, and
- at least one pinion rotatable about a stationary axis for initiating meshing engagement with said rack subsequent to said noncoincident shifting of said magnet end regions, thereby maintaining said elongated magnet substantially parallel to said sorting bars when said magnet is subsequently moved to further separate said desired and undesired cards.

6. The improvement of claim 5 wherein there are at least two racks respectively cooperating with at least two pinions, said cooperating racks and pinions being spaced apart.

7. The improvement of claim 5 further including

- a. a movable plate underlying said card support means and having opposite parallel side edges, said magnet and said racks being mounted for movement with said plate, and
- b. a pair of spaced guide blocks each having a slot for slidably supporting a different one of said opposite plate side edges, said slots being spaced apart a distance exceeding the distance between said opposite plate side edges to permit said plate and magnet to skew during said time-staggered partial separation of said desired and undesired cards.

8. A method of sorting desired cards each having a predetermined notch pattern along a sorting edge and a ferromagnetic member in a transverse edge from undesired cards each having a different notch pattern and a ferromagnetic member in a transverse edge, said method comprising:

disposing said cards in a position with the sorting and transverse edges of said cards in alignment, and with said ferromagnetic members in alignment and magnetically attracted to an elongated magnet disposed common to all said cards,

selectively moving sorting bars disposed in registry with said notches into engagement with the notches of said predetermined pattern, and

noncoincidentally moving opposite end regions of said magnet relative to first and second groups of cards respectively associated therewith for partially separating in a time-staggered manner desired and undesired cards in said first and second groups.
